UNITED STATES PATENT OFFICE

HENRY K. SANDELL, OF CHICAGO, ILLINOIS, ASSIGNOR TO MILLS NOVELTY COMPANY, OF CHICAGO, ILLINOIS, A CORPORATION OF ILLINOIS

TELEVISION LAMP

Application filed June 12, 1930. Serial No. 460,648.

This invention relates to the art of television, and particularly to an improved form of lamp for transforming the television signals into corresponding light signals.

5 An important object of the invention is to provide a television lamp having electrode plates which are shaped to concentrate the light generated in the lamp so as to give a more intense beam for projection on a screen 10 or other image receiving area.

Further objects and advantages of the invention will be apparent as I proceed with my specification, which, taken in connection with the accompanying drawings, discloses a preferred embodiment thereof.

In the drawings:

Fig. 1 is a side elevational view of the lamp;

20 Fig. 2 is a front elevational view of the lamp; and

Fig. 3 is a broken detail view of the electrode plates of the lamp.

Referring to the drawings in which I have shown the preferred form in which I have 25 thus far contemplated applying the principles of my invention, the numeral 5 designates a lamp bulb which may be of the usual form employed for ordinary vacuum tubes, and the numeral 6 designates a base for supporting the bulb 5. A pair of terminal posts 7 and 8 are sealed in the base and project therefrom sufficiently to permit connection with the source of signal current supply. The bulb 5 is gas-filled, a preferred composition of the gaseous medium for this purpose 30 being about five per cent. helium and ninety-five per cent. neon. It will be understood that the lamp is connected in the usual manner in the plate circuit of the last amplifying 35 tube of a multiple stage amplifier, much as in the manner of connection of a loud speaker in the ordinary radio amplifying circuit.

40 According to the invention, the television lamp is provided with a positive electrode 9 and a negative electrode 10 positioned adjacent and parallel to electrode 9. Each of these electrodes comprises a rectangular metal plate, the opposite halves of which are bent to form an angle of about 90 degrees. 45 The positive electrode 9 is connected with

the post 7 by a pair of wires 11, and the negative electrode 11 is connected with the post 8 by a pair of wires 12. The wires 12 may be sealed in a glass housing 13 to prevent danger of shorting with the wires 11. The bending 55 of the electrode plates 9 and 10 in the manner shown tends to greatly concentrate the light generated in the lamp. In lamps of this type the light is generated for the most part on the side or area of the negative plate 10 60 which is most remote from the positive plate 12. The inner face of the plate 10, therefore, may be considered as the active area from the standpoint of generation of light. The plate is positioned with its angular 65 opening facing the point of image reception, which in the accompanying drawings is assumed to be to the right, viewing Fig. 1, and the plate 9 is positioned in back of and parallel to the plate 10.

70 By positioning the opposite halves of the plate 10 at an angle to the line of light projection a greater depth of the glowing gas adjacent the inner surface of plate 10 is utilized to give a more intense illumination for 75 a given plate area than would be obtained with the plate in a position at right angles to the line of vision or light projection. Furthermore, by making the opposite halves of the plate intersect in this manner a portion of 80 the light generated on the lower half of plate 10 will be reflected from the upper half of the plate toward the point of image reception, and similarly light generated on the upper half of plate 10 will be reflected from the 85 lower half of the plate toward the point of image reception. This reflection of light tends to augment the concentration obtained by positioning the active areas of the plate at an angle to the line of vision. In actual 90 practice it has been found that by using this form of electrode, together with a suitable condensing lens, a beam of light may be obtained which is about five times as strong as that obtainable from a lamp having the ordinary flat electrode plate.

95 The invention permits the use of much smaller electrode plates in the lamp, inasmuch as for a given generating plate area a much stronger light beam is obtained than 100

in the case of the flat plate electrode. This is an important factor from the standpoint of inductance. The use of small plates decreases the inductance of the lamp, and hence 5 fewer amplifying tubes need be used to operate the lamp. This, in turn, tends to make for a sharper picture, since each additional tube in the amplifying system adds inductance to the circuit which tends to decrease 10 the sharpness of the reproduced image.

While I have shown the electrode plates as bent to approximate a right angle, it will be apparent that more or less concentration of light can be obtained by using curved plates.

15 For example, plates formed to approximate a parabola opening toward the point of image reception would tend to concentrate the light emanating from the inner surfaces of the plate 10. Such modifications are to be 20 viewed as fully within the scope of the invention. Also, it is to be understood that the shape of the plates need not necessarily be rectangular since this is considered merely a preferred form.

25 The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

30 1. A television lamp comprising a sealed envelope having positive and negative electrodes positioned therein, said negative electrode being in the form of a plate bent to form an angle of approximately ninety degrees, said angle opening away from the positive electrode.

35 2. A television lamp comprising a sealed envelope having positive and negative electrodes positioned therein, said negative electrode being in the form of a plate bent to form an angle of approximately ninety degrees, said angle opening away from the positive electrode, and a positive electrode comprising a plate bent to a similar angle and lying in parallel spaced relation to the negative electrode plate.

40 45 50 55 50 In witness whereof, I hereunto subscribe my name to this specification.

HENRY K. SANDELL.
